UNITED STATES PATENT OFFICE

2,657,634

HYDRAULIC PUMP

Leonard S. Greenland, Compton, Wolverhampton, and Thomas Edwards, Bilbrook, near Wolverhampton, England, assignors to H. M. Hobson Limited, London, England, a company of Great Britain

Application October 19, 1950, Serial No. 191,066

9 Claims. (Cl. 103—38)

1

This invention relates to variable-delivery hydraulic pumps of the type comprising a plurality of pump barrels and associated plungers, a cam shaft, a cam mechanism operated by the cam shaft for effecting reciprocation of the pump plungers in their barrels, the pump barrels being coupled in pairs to delivery lines, allocated one to each pair of pump barrels, and the cam mechanism being so designed that the two pump plungers of each pair cooperate to produce, at each setting of the delivery control mechanism of the pump, a constant rate of flow of liquid in their associated delivery line, one plunger executing a suction stroke while the other is executing a delivery stroke, and means for varying the stroke imparted by the cam mechanism to the plungers and therefore the delivery of the pump.

In U. S. Patent No. 2,553,063 we have described a pump of this type in which the plungers are operated from the cam mechanism through the agency of rocker arms pivoted to a regulating sleeve, which is rotatable in relation to the cam shaft so as to vary the effective length of the rocker arms and therefore the stroke of the plungers. In this form of pump spring-loaded poppet-type inlet and discharge valves were associated with each pump barrel.

We have found, however, that the use of valves of this kind results in some degree of non-uniformity in delivery from the pump at low speeds. Apparently incorrect seating of the valves and variations in spring characteristics prevent correct matching of the delivery from the pairs of connected barrels at low speed and small delivery. The object of this invention is to provide an improved form of valve gear.

The invention accordingly provides a hydraulic pump of the above type, in which the valves controlling the inlet of liquid to and its discharge from the pump barrels are operated mechanically from the cam shaft. We find that by positively opening and closing the inlet and discharge ports associated with the pump barrels, undesirable pulsation in the flow from the pump is eliminated.

In the preferred form of the invention, as applied to a pump of the kind described in U. S. Patent No. 2,553,063, the pump barrels are arranged radially in relation to the cam shaft in a plurality of aligned groups, and a rotary valve is associated with each group of barrels, the valves being positively oscillated to and fro by an eccentric or the equivalent driven by the cam shaft and being formed with inlet and dis-

2

charge ports which are brought alternatively into register with the pump barrels at the appropriate times in the cycle of rotation of the cam shaft.

As in the case of the pump described in U. S. Patent No. 2,553,063, variation of the position of adjustment of the regulating sleeve in relation to the cam shaft will alter the moment in the cycle of rotation of the cam shaft at which the delivery stroke of any given plunger will cease. Provision is therefore made for automatic adjustment in phase of the eccentric in relation to the cam shaft on rotation of the regulating sleeve, so as to effect corresponding change in the timing of the movement of the rotary valves.

Two embodiments of the pump according to the invention, suitable for supplying fuel to a gas turbine engine, will now be described in detail, by way of example, with reference to the accompanying drawings, in which:

Fig. 1 is a cross section through the first form of pump taken on the line I—I in Fig. 2.

Fig. 2 is a section on the line II—II in Fig. 1. Figs. 3—7 are respectively sections on the lines III—III, IV—IV, V—V, VI—VI and VII—VII in Fig. 2, Figs. 3 and 4 being on a larger scale, and Fig. 5 showing the eccentric in a position different from that shown in Fig. 2.

Figs. 8—13 are diagrammatic views, similar to Figs. 3 and 4 showing the positions assumed by one of the rotary valves at different points in the stroke of one of the associated pump plungers.

Fig. 14 is a part longitudinal section through the second form of pump, and

Fig. 15 is a fragmentary view of part of its mechanism for changing the phase of the eccentric in relation to the cam shaft.

Like reference numerals designate like parts throughout the figures.

Apart from the valve gear, the pump shown in Figs. 1—13 is of the general construction described in U. S. Patent No. 2,553,063. The pump has sixteen pump barrels 20 arranged radially, in aligned groups of four, spaced 90° apart in relation to a central cam shaft 121. Fig. 1 shows one of each of the four groups of pump barrels, while Fig. 2 shows the top group of four aligned pump barrels. The four pump barrels of each group are coupled in pairs, as later described, to two delivery lines 21, 22 (Fig. 6) communicating with two delivery outlets 23, 24. There are thus eight delivery outlets for the sixteen pump barrels and these serve to supply fuel

to the eight injection nozzles (not shown) of a gas turbine.

The cam shaft 121 carries two cams 25, arranged in anti-phase i. e. 180° out of phase with one another, which actuate the pump plungers 26 on their delivery stroke through the agency of rocker arms 27 (Fig. 1), pivotally mounted on pins 28 carried by a regulating sleeve 29 surrounding the cam shaft 121. The rocker arms 27 carry rollers 31, rotatably mounted on the 10 rocker arms by pins 32, and springs 30 hold the rollers 31 in contact with the cams 25. The plungers 26 are returned by springs 33 on the suction stroke, the springs 33 bearing against tappets 34 attached to the inner ends of the plungers 26. Each rocker arm 27 coacts with the tappets 34 of a pair of adjoining pump plungers 26, as shown in Fig. 2, and alternate pump barrels in each group communicate with a common discharge passage 21, 22. Thus the 20 first barrel 29 of the group reading from the left hand side of Fig. 2, which is operated by the left hand cam 25, and the third barrel from the left of that group, which is operated by the other cam 25, discharge into the common discharge passage 21. The second and fourth barrels of the group communicate with the other common delivery passage 22.

The one plunger of each coupled pair of barrels is thus executing a suction stroke while the other is executing a delivery stroke, and the cams 25 are so shaped that, when the discharge from one barrel of the pair is increasing, immediately following its suction stroke, that from the other barrel is correspondingly decreasing, while when the discharge from one barrel is decreasing, immediately following its delivery stroke, that from the other barrel is correspondingly increasing.

The regulating sleeve 29 is coupled to a boss 100 carrying four servo vanes 35 (see Figs. 2 and 7). The servo vanes 35 (see Fig. 7) are rotatable, for the purpose of rotating the sleeve 28 and thereby varying the delivery of the pump, in their respective sections of a housing defined by four radial walls 101 in the pump casing. In the boss 100 are formed four passages 102, and four passages 103, longitudinally offset from the passages 102. Fixed to the boss 100 is a tubular insert 104 in which are formed a pair of peripheral grooves 105, 106 adapted to cooperate respectively with the passages 102, 103. Two radial ports 109 in the insert communicate with the groove 105 and two radial ports 110 in the insert communicate with the groove 106.

Inside the insert 104 is mounted a sleeve valve 107, having a spigot 108 to which are fixed a manual operating lever (not shown) and also a pointer (likewise not shown) which coacts with a scale on the end wall of the pump housing to indicate the delivery for which the pump is set. In the outer surface of the valve 107 are provided two longitudinal ports 111 which communicate, in all positions of adjustment of the valve, with an inlet 112 for oil under pressure and a pair of lands 113 on the valve normally seal the ports 109. Two other ports 114 in the valve communicate with the interior 120 of the valve, and thence with the interior of the pump casing, and lands 115 on the valve normally seal the ports 110.

If the valve 107 is turned anticlockwise from the position shown in Fig. 7, oil under pressure is supplied, from the ports 111 and the ports 109 to the passages 102, while the passages 103 are connected, through the port 106 and the ports 75

114 to the interior of the valve 107. The vanes 35 therefore rotate anticlockwise as seen in Fig. 7, to effect corresponding movement of the sleeve 29, oil being expelled through the interior of the valve 107 to the pump casing where it serves to lubricate the pump. The movement ceases when the insert has been rotated sufficiently for the ports 109, 110 to be again sealed by the lands 113, 115 on the valve 107.

Obviously, the reverse state of affairs will prevail when the valve 107 is rotated clockwise as seen in Fig. 7, oil under pressure then being supplied to the ports 103 and the ports 102 being connected to the interior of the valve 107, with the result that the vanes 35 will rotate clockwise.

In all positions of the servo vanes 35 the plungers 26 are positively moved by the cams 25 to the outer ends of the barrels on the delivery stroke, the distance to which they may be returned by their springs 33, on the suction stroke, varying however with the effective length of the rocker arms 27.

Associated with each group of pump barrels is a rotary valve 36, carrying a crank pin 37 (Fig. 5) coupled, by a link 38, to an eccentric 39 driven by the cam shaft 121 and common to all the valves. Each crank pin 37 is supported by a member 40 (Fig. 2) coupled to the valve 36 by a key 41, the outer end of the link 38 being accommodated in a cut-away portion 42 (Fig. 5) of the member 40. Each of the valves 36 is oscillated to and fro by the eccentric 39 to establish corresponding inlet and discharge connections to and from the associated pump barrels. It will be sufficient to describe but one of the valves 36, viz., that shown in Fig. 2.

Fuel from a fuel inlet passage 43 common to all the valves 36 passes, via an annulus 44, an inlet conduit 45 and a port 46 in the valve into a central passage 47 in the interior of the valve. The passage 47 communicates with four radial inlet ports 48 in the valve, one for each pump barrel. These ports 48 are relatively staggered, having regard to the fact that two of the plungers will be executing suction strokes while the other two are executing delivery strokes. The suction ports 48 are brought, by movement of the rotary valve 36, into register with the ends of the pump barrels remote from the cam shaft at the appropriate times in the cycle of rotation of the cam shaft.

Surrounding the valve 36 is a fixed sleeve 49 having in it four arcuate grooves. Two of these grooves 50, namely those associated with the first and third pump barrels from the left of the group, communicate, as shown in Fig. 6, via ports 51 with the discharge passage 21. The other two annular grooves 52, namely those associated with the second and fourth pump barrels from the left, communicate, via ports 53, with the other discharge passage 22. The valve 36 has four arcuate discharge ports 54 (Figs. 3 and 4) each of which cooperates with an associated port 55 in the sleeve 49. The sleeve 49 has four ports 56, one communicating with each of the pump barrels.

When any plunger 26 is in bottom dead centre position the valve 36, which is rotating clockwise as seen in Fig. 8, occupies the position shown in that figure, in which it closes the port 56. As the plunger begins its delivery stroke, the valve 36 moves clockwise into the position shown in Fig. 9, in which the port 54 is brought into co-operation with the port 56, so allowing fuel to be

expelled from the pump barrel, through the ports 56, 54, 55 to the annular groove 50 or 52 in the sleeve 49, and thence to the delivery passage 21 or 22. Figure 10 shows the position of the valve 36 at the completion of its clockwise movement, the plunger 26 having performed about half of its delivery stroke. In Fig. 11, the plunger 26 has nearly completed its delivery stroke and the valve 36 has begun its movement in the counter-clockwise direction, the port 56 still being in communication with the port 54. In Fig. 12 the plunger 26 has reached its top dead centre position, and the valve 36 has moved into position to close the port 56. As the plunger 26 commences its suction stroke the valve 36 moves counter-clockwise into the position shown in Fig. 13, in which the suction port 48 in the valve is in co-operation with the port 56. At the limit of the counter-clockwise movement of the valve 36, the suction port 48 is fully in register with the port 56. Then, as the valve 36 commences its clockwise movement, the suction port 48 is gradually brought out of register with the port 56 until the bottom dead centre position of the plunger is reached (Fig. 8). The above-described cycle of operations is then repeated.

The valve 36 is provided with "idle" ports 148, 154 which are respectively situated opposite each of the inlet 48 and discharge ports 54. These idle ports ensure that the valve is hydraulically balanced and is not subject to side loads which might cause it to stick. As shown in Fig. 9, the side load to which the valve 36 is subjected, during the discharge stroke, by the pressure of the fuel in the discharge port 54, is balanced by the pressure of the fuel in the idle port 154 which is then open to the groove 50 through a port 57 in the sleeve 49.

As explained above, it is necessary, when the regulating sleeve 29 is rotated relatively to the cam shaft 121 by the servo vanes 35, for the eccentric 39 to receive a corresponding rotational movement to adjust its phase relation to the cam shaft.

The eccentric 39 is rotatably mounted on the cam shaft 121 and carries one sun wheel 58 of a differential gear. The other sun wheel 59 is fixed to the cam shaft 121 and drives the eccentric through the agency of planet wheels 60 on a planet carrier 61. A bevel pinion 62 loosely mounted on the spindle of one of the planet wheels 60 meshes with a fixed sun wheel 63 and with a bevel wheel 64 fixed to the sleeve 29.

Normally, therefore, the planet carrier 61 remains stationary. When, however, the regulating sleeve 29 is rotated, the bevel wheel 64 turns with it, thereby rotating the planet carrier 61 about the axis of the cam shaft and effecting a corresponding rotation of the sun wheel 58, and of the eccentric 39, about the axis of the cam shaft.

The pump shown in Figs. 14 and 15 is similar in all its essentials to that shown in Figs. 1-13, but has a different mechanism for adjusting the phase relationship of the eccentric to the cam shaft. In this case a boss 65, to which the servo vanes are attached, has an internal thread 66 engaging a helically threaded member 67 supported by a bearing 68 so that it may rotate on a rod 69 mounted in a cavity 70 in the cam shaft 121. Collars 71 on the rod 69 coact with the member 67 so that, as the boss 65 of the servo vanes rotates axial movement will be imparted to the rod 69. The rod 69 carries a key 72 having projections 73 passing through opposed axial 75

slots 74 in the cam shaft and engaging inclined grooves 75 (see Fig. 15) in the boss of the eccentric 39. The key 72 serves to couple the eccentric 39 and rod 69 to the cam shaft 121 so that they rotate with it. As will readily be understood, the axial movement imparted to the rod 69 when the servo vanes rotate to impart rotational adjustment to the regulating sleeve 29 will, through the coaction of the projections 73 with the helical slots 75, effect rotational adjustment of the eccentric 39 in relation to the cam shaft 121.

What we claim as our invention and desire to secure by Letters Patent is:

1. A hydraulic pump, comprising a cam shaft, pump barrels disposed radially in relation to the cam shaft and arranged in a plurality of groups, with the barrels of each group having their axes disposed parallel to one another in a common axial plane of the cam shaft, a plunger mounted to reciprocate in each pump barrel to perform suction and delivery strokes, an inlet for liquid, the pump barrels being arranged in pairs and each pair of pump barrels having a common delivery outlet, a cam mechanism on the cam shaft for reciprocating the plungers in their respective pump barrels, means for regulating the delivery strokes of said plungers, said cam mechanism being so shaped that the flow of liquid in each delivery outlet is constant and determined in magnitude by the setting of said regulating means, an oscillatory valve associated with each group of pump barrels, and valve actuating means driven by the cam shaft for oscillating all of said valves, said valves having inlet and discharge ports for connecting the associated pump barrels to said inlet, during the suction strokes of the plungers in said barrels, and to the associated delivery outlet, during the delivery strokes of the plungers in said barrels.

2. A hydraulic pump, comprising a cam shaft, pump barrels disposed radially in relation to the cam shaft and arranged in a plurality of groups, with the barrels of each group having their axes disposed parallel to one another in a common axial plane of the cam shaft, a plunger mounted to reciprocate in each pump barrel to perform suction and delivery strokes, an inlet for liquid, the pump barrels being arranged in pairs and each pair of pump barrels having a common delivery outlet, a cam mechanism on the cam shaft for reciprocating the plungers in their respective pump barrels, a regulating sleeve surrounding said cam shaft and rotatable in relation thereto, rocker arms pivoted to said sleeve for imparting reciprocating movement from said cam mechanism to said plungers, said cam mechanism being so shaped that the flow of liquid in each delivery outlet is constant and determined in magnitude by the setting of said regulating sleeve, an oscillatory valve associated with each group of pump barrels, an eccentric driven by the cam shaft and arranged to impart oscillating movement to said valves, said valves having inlet and discharge ports for connecting the associated pump barrels to said inlet, during the suction strokes of the plungers in said barrels, and to the associated delivery outlet, during the delivery strokes of the plungers in said barrels, and mechanism linked to said regulating sleeve for effecting, on rotation of said regulating sleeve, rotational adjustment of said eccentric in relation to said cam shaft.

3. A hydraulic pump as claimed in claim 2, in which the mechanism for effecting rotational adjustment of said eccentric comprises a differ-

ential gear, including a sun wheel fixed to the eccentric, a sun wheel fixed to the cam shaft, a planet carrier coacting with said sun wheels, a pair of further sun wheels, one of which is fixed and the other attached to the regulating sleeve, and a toothed wheel mounted on said planet carrier and meshing with both of said further sun wheels.

4. A hydraulic pump as claimed in claim 2, in which the mechanism for effecting rotational adjustment of said eccentric comprises a rod mounted for axial displacement within the cam shaft, a projection on said rod engaging an axial slot in the cam shaft and an inclined slot in the eccentric, an externally threaded member mounted to turn on said rod, means holding said member against axial movement in relation to said rod, and an internally threaded boss on the regulating sleeve engaging said externally threaded member.

5. A hydraulic pump as claimed in claim 1, in which each group of aligned pump barrels comprises four pump barrels, in which the cam mechanism comprises two cams of the same shape but displaced 180° in phase, each cam being arranged to actuate the plungers in a pair of adjoining pump barrels in each group, and in which each valve controls communication between the pump barrels of the associated group and a pair of delivery passages, each delivery passage receiving the discharge from two pump barrels, one allotted to each cam.

6. A hydraulic pump as claimed in claim 5, comprising sleeves surrounding the valves, each valve having a central bore communicating with the inlet, four inlet ports and four delivery ports, the delivery ports communicating alternately with the two delivery passages through ports in the associated valve sleeve.

7. A hydraulic pump as claimed in claim 6, in which each valve is formed with idle ports opposite the inlet and discharge ports therein, said idle ports serving to provide hydraulic balance for said valve.

8. A hydraulic pump comprising a shaft, a pair of pumping units, each pumping unit comprising a barrel disposed radially in relation to the shaft and a plunger in said barrel, an inlet for liquid, a delivery outlet common to and arranged to receive the discharge from said pair of pumping units, a cam mechanism on the shaft for reciprocating the plungers in their respective barrels, a regulating sleeve surrounding the cam mechanism, rocker arms pivoted to the sleeve on axes parallel to that of the shaft for imparting movement from the cam mechanism to the plungers, means for rotating said sleeve in relation to the shaft so as to vary the effective length of the rocker arms and therefore the delivery of

the pump, said cam mechanism being so shaped that the flow of liquid in said delivery outlet is constant and determined in magnitude by the position of rotational adjustment of said sleeve in relation to said shaft, an oscillatory valve common to the barrels of said pumping units, an eccentric driven by said shaft for imparting rocking movement to said valve, said valve having inlet and discharge ports for connecting each of said barrels to said inlet, during the suction strokes of the plunger in said barrel, and to said delivery outlet, during the delivery strokes of the plunger in said barrel, and mechanism linked to said regulating sleeve for effecting, on rotation of said regulating sleeve, rotational adjustment of said eccentric in relation to said shaft.

9. A hydraulic pump comprising a shaft, a pair of pumping units, each pumping unit comprising a barrel disposed radially in relation to the shaft and a plunger in said barrel, an inlet for liquid, a delivery outlet common to and arranged to receive the discharge from said pair of pumping units, a cam mechanism on the shaft for reciprocating the plungers in their respective barrels, a regulating sleeve surrounding the cam mechanism, rocker arms pivoted to the sleeve on axes parallel to that of the shaft for imparting movement from the cam mechanism to the plungers, means for rotating said sleeve in relation to the shaft so as to vary the effective length of the rocker arms and therefore the delivery of the pump, said cam mechanism being so shaped that that flow of liquid in said delivery outlet is constant and determined in magnitude by the position of rotational adjustment of said sleeve in relation to said shaft, an oscillatory valve common to the barrels of said pumping units, valve actuating means on said shaft for imparting rocking movement to said valve, said valve having inlet and discharge ports for connecting each of said barrels to said inlet, during the suction strokes of the plunger in said barrel, and to said delivery outlet, during the delivery strokes of the plunger in said barrel, and mechanism linked to said regulating sleeve for effecting, on rotation of said regulating sleeve, phase adjustment of said valve actuating means with respect to said shaft.
